ABSTRACT

The invention relates to a built-in antenna module for a wireless communication terminal. The module includes at least one radiator. The module also includes a base having an inner space, disposed on a board of a terminal body, and having the radiator on an outer surface thereof to enable electric connection between an end of the radiator and the board of the terminal body. The module further includes an operator disposed in the inner space of the base for indicating an incoming call when power is supplied. The invention efficiently utilizes a limited space in the terminal body with enhanced capabilities of the antenna.

BUILT-IN ANTENNA MODULE OF WIRELESS
COMMUNICATION TERMINAL

CLAIM OF PRIORITY

This application claims the benefit of Korean Patent Application No. 2005-39044 filed on May 10, 2005, in the Korean Intellectual Property Office, the disclosure of which is incorporated herein by reference.

BACKGROUND OF THE INVENTION

1. Field of the Invention

The present invention relates to an antenna installed inside a wireless communication terminal, and more particularly, a built-in antenna module for a wireless communication terminal, in which an operator for generating sounds or vibrations indicating an incoming call is housed in a component, thereby efficiently utilizing a limited space in a miniaturized wireless communication terminal.

2. Description of the Related Art

In general, a wireless communication terminal refers to a portable communication device capable of transmitting and receiving voices and texts and image data through wireless communication. The examples include a personal communication service (PCS) terminal, a Personal Digital Assistant (PDA), a smart phone, a next-generation mobile communication (IMT-2000) terminal, a wireless LAN terminal and the like.

The wireless communication terminal adopts a helical antenna or a dipole antenna to enhance its transmission and reception sensitivity. These are external antennas, which thus are extended out of the wireless terminal.

The external antennas have an advantage of non-directional radiation characteristics. But as they are extended to the outside, they are much likely to be damaged by external force, inconvenient for carrying around, and may be a hindrance to attractive exterior design of the terminal.

To overcome such a problem, plate-shaped built-in antennas such as a micro-strip patch antenna or inverted F-type antenna are adopted in the wireless communication terminal recently since they can be installed in the terminal without being extended outward.

FIG. 1 is an assembly diagram in which a built-in antenna and an actuator are provided in a wireless communication terminal according to the prior art. As shown, an antenna module 2 is hooked detachably onto a board 1 of a terminal body (not shown).

The antenna module 2 includes a buttress 3 having a plurality of fastening legs 3a corresponding to fastening grooves 1a formed on the board 1, a conductor 4 shaped like a metal plate on an upper surface of the buttress 3, and a feeder 5 extended from the conductor 4 to be inserted into a contact hole 1b.

Installation of such an antenna module 2 in a terminal body allows more attractive exterior of the terminal with greater portability. In a miniaturized terminal, however, in order to retain or enhance the current transmission and reception efficiency and frequency reception capabilities, the size of the installation area of the antenna prior to miniaturization needs to be maintained or increased.

However, with the limited space in the miniaturized terminal body, it is difficult to maintain or increase the installation area of the antenna.

Furthermore, a part of the board 1 needs to be preserved for disposing an actuator such as a vibration motor 12 for generating vibrations or a speaker 11 for generating sounds indicating an incoming call. Thus, in case of disposing the antenna module 2 coplanar with the actuator 10, there is a limitation in increasing the space for the antenna module to enhance the capabilities of the antenna.

2

cating an incoming call. Thus, in case of disposing the antenna module 2 coplanar with the actuator 10, there is a limitation in increasing the space for the antenna module to enhance the capabilities of the antenna.

5

SUMMARY OF THE INVENTION

The present invention has been made to solve the foregoing problems of the prior art and it is therefore an object of the present invention to provide a built-in antenna module which efficiently utilizes a limited space in a terminal body with improved capabilities of an antenna.

According to an aspect of the invention for realizing the object, there is provided a built-in antenna module for a wireless communication terminal including:

at least one radiator;

a base having an inner space, disposed on a board of a terminal body, and the base having the radiator on an outer surface thereof to enable electric connection between an end of the radiator and the board of the terminal body; and

an operator disposed in the inner space of the base for indicating an incoming call when power is supplied.

Preferably, the radiator has the same dimensions as the upper surface of the base in order to maximize transmission and reception capability of the antenna.

Preferably, the radiator is a plate-shaped antenna pattern assembled detachably onto the outer surface of the base.

Preferably, a resilient terminal is extended in a predetermined length from an end of the radiator to a lower surface of the base.

Preferably, the radiator is an antenna pattern printed on an outer surface of the base.

Preferably, the base includes an upper base and a lower base assembled together to form an inner space therein for internally housing the operator.

More preferably, the upper base has a plurality of insertion projections on an upper surface thereof corresponding to insertion holes of the radiator.

More preferably, the upper base has a plurality of vertical pillars on an undersurface thereof corresponding to a plurality of lower holes formed in the upper surface of the lower base.

More preferably, the upper base has at least one insertion flap on an outer periphery thereof corresponding to insertion grooves formed on an outer periphery of the lower base.

More preferably, the built-in antenna module further includes a gasket between the upper base and the lower base for preventing sounds generated by the operator from leaking out of the base.

More preferably, the upper base and the lower base are bonded integrally with an adhesive to prevent sounds generated by the operator from leaking out of the base.

More preferably, the upper base and the lower base are bonded integrally via ultrasonic welding to prevent sounds generated by the operator from leaking out of the base.

More preferably, one of the upper and lower bases includes a seating part depressed for precisely locating the operator.

More preferably, the seating part has a predetermined dimension of sound emitting opening, and one of the upper and lower bases comprises a sound passageway having an opening at an end facing a receiver to deliver the sound emitted from the sound emitting opening to the receiver of the terminal body.

More preferably, the lower base has a plurality of projections corresponding to holes formed in the board.

Preferably, the base is fastened with a fastening member such that the lower surface of the base is in surface contact with the upper surface of the board.

65

Preferably, the base is made of insulation material.

Preferably, the operator has at least one multi-actuator for selectively generating sounds or vibrations when power is supplied.

More preferably, one of the upper and lower bases corresponding to the multi-actuator has an opening for delivering the generated sounds to a receiver of the terminal body.

Preferably, the operator includes at least one first actuator for generating sounds when power is supplied and at least one second actuator for generating vibrations when power is supplied.

More preferably, one of the upper and lower bases corresponding to the first actuator has an opening for delivering the generated sounds to a receiver of the terminal body.

More preferably, one of the upper and lower bases corresponding to the second actuator is sealed to deliver the generated vibrations through the base to the terminal body.

More preferably, the lower base with the second actuator disposed therein comprises a plurality of vertical ribs in contact with an outer surface of the second actuator.

BRIEF DESCRIPTION OF THE DRAWINGS

The above and other objects, features and other advantages of the present invention will be more clearly understood from the following detailed description taken in conjunction with the accompanying drawings, in which:

FIG. 1 illustrates assembly of a built-in antenna and an actuator provided in a terminal according to the prior art;

FIG. 2 illustrates a built-in antenna module for a wireless communication terminal according to a first embodiment of the present invention, in which (a) is a top perspective view, and (b) is a bottom perspective view;

FIG. 3 is an exploded perspective view illustrating the built-in antenna for the wireless communication terminal according to the first embodiment of the present invention;

FIG. 4 illustrates an upper base adopted in the built-in antenna for the wireless communication terminal according to the first embodiment of the present invention, in which (a) is a plan view, (b) is a front view, and (c) is a side view;

FIG. 5 illustrates a lower base adopted in the built-in antenna for the wireless communication terminal according to the first embodiment of the present invention, in which (a) is a plan view, (b) is a bottom view, and (c) is a front view;

FIG. 6 illustrates the assembly flow of the built-in antenna for the wireless communication terminal according to the first embodiment of the present invention;

FIG. 7 is an exploded perspective view illustrating a built-in antenna for a wireless communication terminal according to a second embodiment of the present invention; and

FIG. 8 illustrates the assembly flow of the built-in antenna for the wireless communicative terminal according to the second embodiment of the present invention.

DETAILED DESCRIPTION OF THE PREFERRED EMBODIMENT

Preferred embodiments of the present invention will now be described in detail with reference to the accompanying drawings.

As shown in FIGS. 2 to 6, in an antenna module 100 of the present invention, an antenna component for transmitting and receiving an electrical wave is integrated with a component for generating sounds or vibrations indicating an incoming call, thereby efficiently utilizing an inner space of the wireless communication terminal. The antenna module 100 includes a radiator 110, a base 120 and an operator 130.

The radiator 110 is composed of at least one conductor disposed on an outer surface of the base 120. During a telephonic communication, the radiator 110 receives an electric signal from a board M provided in the terminal body, transforming the signal into an electrical wave to be radiated to the outside while receiving an electrical wave in a particular frequency band transmitted from the outside.

In addition, as shown in FIG. 2(a), it is preferable that the radiator 110 is formed in substantially the same dimensions as the upper surface of the base 120 in order to maximize the transmission and reception capabilities of the antenna.

Such a radiator 110 may be a plate-shaped antenna pattern detachably assembled onto an outer surface of the base 120 with a plurality of projections 125 formed on an outer surface of the base inserted into a plurality of holes 115 formed in the radiator, but is not limited to such and can be varied depending on the designing of the pattern.

As shown in FIG. 2(c), an end of the radiator 110 is extended in a predetermined length to the lower surface of the base 120 to integrally form at least one resilient terminal. The resilient terminal 111 becomes electrically connected to a pattern circuit formed on the board M of the terminal body 101 as the radiator 110 and the base 120 are assembled together.

Here, it is preferable that the radiator 110 adopts a plate-shaped antenna such as a micro-strip patch antenna or inverted F-type antenna.

The radiator 110 may be an antenna pattern printed on an outer surface of the base 110 to be electrically connected with the pattern circuit of the board.

In addition, the base 120 is a structure made of insulation material and detachably assembled onto the board M such that the resilient terminal 111 extended from an end of the radiator 110 is electrically connected with the board M of the terminal body 101.

As shown in FIGS. 2(a) and (b) to 5(a) and (b), the base 120 is composed of an upper base 120a and a lower base 120b assembled together to provide a space for internally housing an operator which generates sounds or vibrations indicating an incoming call when power is supplied.

The upper base 120a has a plurality of projections 125 on an upper surface thereof inserted into a plurality of holes 115 formed in the radiator 110. Also, the upper base 120a has a plurality of vertical pillars 121 protruded from a lower surface thereof inserted into a plurality of lower holes 123 formed on an upper surface of the lower base 120b.

The upper base 120a has at least one insertion flap 122 on an outer surface thereof inserted into insertion grooves 124 formed on an outer surface of the lower base 120b. The insertion flaps 122 and the insertion grooves 124 form a structure that determines an angle and direction of terminals 131a and 132a as well as providing protection for the terminals 131a and 132a as the terminals 131a and 132a are drawn to the outside.

The upper and lower bases 120a and 120b are easily assembled together via one-to-one assembly of the vertical pillars 121 and the lower holes 123, and form a predetermined dimension of space therebetween for housing the operator 130.

Here, a gasket 120c made of rubber may be provided between the upper and lower bases 120a and 120b to prevent the sounds generated by the operator 130 from leaking out of the base, but the present invention is not limited to such. The upper and lower bases 120a and 120b can be integrally bonded by an adhesive or via ultrasonic welding.

In addition, at least one guide rib 126 can be protruded from one side of an upper surface of the upper base 120a such

that the resilient terminals 111 extended from an end of an upper surface of the upper base 120a are in alignment therewith.

In addition, in order to precisely locate the operator 130, a seating part 127 is depressed in a predetermined depth on an upper surface or a lower surface of the base 120 corresponding to an upper surface or a lower surface of the operator 130. Such a seating part 127 has a predetermined dimension of sound emitting opening 127a so that the sounds generated from the operator 130 are emitted to the board M and delivered without any loss through a receiver 108 disposed on a side of the terminal body 101 to the outside.

Here, it is preferable that the inner circumference of the sound emitting opening 127a is larger than the outer circumference of the operator 130, preventing the operator 130 from slipping downward.

In addition, in case of forming the sound emitting opening 127a in a lower surface of the lower base 120b, it is preferable that the lower base 120b has a sound passageway 128 having an opening 128a on an end facing the receiver 108 in order to facilitate delivery of the sounds emitted from the sound emitting opening 127a to the receiver of the terminal body 101. The same can be applied to a sound emitting opening formed in the upper base 120a.

With the above configuration, the sounds generated from the operator 130 pass through the sound emitting opening 127a and the sound passageway 128 and through the receiver 108 of the terminal body 101 to the outside, and finally are perceived by the user.

Also, the lower base 120b has a plurality of assembly hooks 129 on an undersurface thereof corresponding to a plurality of assembly holes 109 perforated through an upper surface of the board M to facilitate assembly of the lower base with the board.

With the operator 130 disposed in the inner space of the base 120 composed of the upper and lower bases 120a and 120b assembled together, the assembly hook 129 is vertically aligned with the assembly hole 109 of the board M. Then the base 120 is pressured against the board M such that the end of the assembly hook 129 is resiliently inserted into the assembly hole 109 and hooked inside the assembly hole 109, thereby assembling the base 120 with the operator 130 disposed therein onto the upper surface of the board M.

Here, with the undersurface of the base 120 in surface contact with the upper surface of the board, the resilient terminal 111 for transmission and reception of the radiator 110 is aligned by the guide rib 126 formed in a side of the upper surface of the upper base 120a, and has the lower end thereof in resilient contact with the pattern circuit of the board M.

The base 120 can be assembled onto the board M with the assembly of the assembly hooks 129 of the lower base 120b into the assembly holes 109 of the board M but the present invention is not limited to such.

It is also desirable that the base 120 has screw holes (not shown) corresponding to another set of screw holes (not shown) of the board M so that the base 120 have surface contact with the board M by a plurality of fastening members inserted and connecting through the screw holes facing each other.

Thus, the operator 130 generates vibrations indicating an incoming call which vibrate the base 120 and also the board M in surface contact with the base 120, thereby vibrating the entire terminal body 101.

In the meantime, as shown in FIGS. 3 and 6, the operator 130 is composed of at least one operating means disposed in

the inner space of the base 120, generating sounds or vibrations indicating an incoming call.

The operator 130 is composed of at least one multi-actuator 131 selectively generating sounds or vibrations depending on the choice of the user when power is supplied through a terminal 131a extended outward and connected with a feeder (not shown) of the board M.

It is preferable that the upper or lower surface of the base 120 corresponding to the upper or lower surface of the multi-actuator 131 has an opening so that the generated sounds are delivered through the opening to the receiver 108 of the terminal body 101.

In addition, as shown in FIGS. 3 and 6, the terminal 131a of the multi-actuator 131 may be a flexible board having a connector extended laterally and electrically connected with the pattern circuit of the board M to supply power to the multi-actuator 131. Alternatively, the terminal 131a of the multi-actuator 131 may be a lead electrically solder-connected with the pattern circuit of the board M to supply power to the multi-actuator 131.

FIG. 7 is an exploded perspective view illustrating a built-in antenna for a wireless communication terminal according to a second embodiment of the present invention, and FIG. 8 illustrates assembly of a built-in antenna for a wireless communication terminal according to a second embodiment of the present invention.

The built-in antenna module 100a according to the invention includes a radiator 110, a base 120 and an operator 130a, and the same components are denoted by the same reference numerals with the detailed explanation thereof omitted.

As shown in FIGS. 7 and 8, the operator 130a disposed in the inner space of the base 120 is consisted of at least one first actuator 132 for generating sounds when power is supplied and at least one second actuator 133 generating vibrations when power is supplied.

Here, it is preferable that a seating part 127 formed on the upper or lower surface of the base 120 corresponding to the upper or lower surface of the first actuator 132 has an opening so that the generated sounds are delivered through the opening to a receiver of a terminal body 101. It is also preferable that another seating part 127' formed on the upper or lower surface of the base 120 corresponding to the upper or lower surface of the second actuator 133 is sealed so that the generated vibrations are transmitted through the base 120 to the terminal body 101.

In addition, it is preferable that the seating part 127' with the second actuator 133 disposed therein has a plurality of vertical ribs 127b protruded therefrom which are in resilient contact with the outer surface of the second actuator 133 so that the second actuator 133 is disposed in the exact position without wobbling.

In addition, as shown in FIGS. 7 and 8, terminals 132a and 133a of the first and second actuators 132 and 133 may be leads extended laterally from the actuators 132 and 133 disposed on the upper surface of the lower base 120b and electrically solder-connected to the pattern circuit of the board M to supply power, or may be a flexible board having a connector.

The assembly procedures of the built-in antenna module 100, 100a are shown in FIGS. 6 and 8. First, the operator 130 is disposed in the seating part 127 formed on the upper surface of the lower base 120b.

In case of the operator 130 composed of one multi-actuator 131 selectively generating sounds and vibrations when power is supplied, the multi-actuator 131 is disposed in the seating part 127 having an opening for forming a sound emitting opening 127a, in an upper part of the lower base 120b.

The terminal **131a** extended from the multi-actuator **131** is drawn out through the sound emitting opening **127a** or a terminal hole (not shown) perforated in the seating part **127** and through the lower part of the lower base **120b** to the outside.

In addition, in case of the operator **130** composed of the first actuator for generating sounds when power is supplied and the second actuator **133** for generating vibrations when power is supplied, the first actuator **132** is disposed in the seating part **127** having an opening for forming a sound emitting opening **127a** in an upper part of the lower base **120b**, and the second actuator **133** is disposed in another seating part **127'** with the sealed floor surface of the lower base **120b**.

In addition, each of the terminals **132a** and **133a** extended from the first and second actuators **132** and **133** is extended through the sound emitting opening **127a** or the terminal hole (not shown), out of the lower base **120b**.

Thereafter, with the upper base **120a** vertically aligned on top of the lower base **120b** having the operator **130** disposed thereon, the vertical pillars **121** of the upper base **120a** are assembled one-to-one with the lower holes **123** of the lower base **120b**, thereby assembling the upper and lower bases **120a** and **120b** together.

Thereby, the operator **130** is internally housed in the inner space formed by the upper and lower bases **120a** and **120b** assembled together.

In addition, the projections **125** of the upper base **120a** is inserted into the holes **115** formed in the radiator **110** one-to-one, so that the radiator **110** is integrally assembled onto the upper surface of the upper base **120a**.

At this point, the resilient terminal **111** for transmission and reception extended from an end of the radiator **110** is fitted in between the guide ribs **126** provided on one side of the upper surface of the upper base **120a**, and the end of the resilient terminal **111** is extended in a predetermined length through an outlet formed in the lower base **120b**, out of the undersurface of the lower base **120b**.

The plurality of assembly hooks **129** protruded from the undersurface of the lower base **120b** are inserted one-to-one into the assembly holes **109** of the board **M**, so that the base **120** having the operator **130** therein comes in surface contact with the upper surface of the board **M**, and simultaneously, the resilient terminal **111** becomes electrically connected to the pattern circuit of the board **M**.

In addition, each of the terminals **131a**, **132a**, and **133a** of the operator **130** drawn out of the lower part of the base **120** is electrically connected with the pattern circuit of the board **M**, allowing the operator **130** to generate sounds or vibrations when power is supplied. The sounds generated at this point are delivered to the outside through the receiver **108** of the terminal body **101**, and the vibrations are transmitted through the base **120** to the terminal body **101**, vibrating the entire terminal.

According to the invention set forth above, a base having a radiator thereon has an inner space for internally housing an operator for selectively and individually generating sounds or vibrations to integrate the radiator and the operator in a module, efficiently utilizing the constrained inner space of the terminal body, thereby allowing further miniaturization of the terminal without weakening the transmission and reception capabilities of an antenna.

While the present invention has been shown and described in connection with the preferred embodiments, it will be apparent to those skilled in the art that modifications and variations can be made without departing from the spirit and scope of the invention as defined by the appended claims.

What is claimed is:

1. A built-in antenna module for a wireless communication terminal comprising:
at least one radiator;
a base having an inner space, disposed on a board of a terminal body, and the base having the radiator on an outer surface thereof to enable electric connection between an end of the radiator and the board of the terminal body; and
an operator disposed in the inner space of the base for indicating an incoming call when power is supplied; wherein the base includes an upper base and a lower base assembled together to form an inner space therein for internally housing the operator; and
wherein a gasket is disposed between the upper base and the lower base for preventing sounds generated by the operator from leaking out of the base.
2. The built-in antenna module for a wireless communication terminal according to claim 1, wherein the radiator has the same dimensions as the upper surface of the base in order to maximize transmission and reception capability of the antenna.
3. The built-in antenna module for a wireless communication terminal according to claim 1, wherein the radiator comprises a plate-shaped antenna pattern assembled detachably onto the outer surface of the base.
4. The built-in antenna module for a wireless communication terminal according to claim 1, wherein a resilient terminal is extended in a predetermined length from an end of the radiator to a lower surface of the base.
5. The built-in antenna module for a wireless communication terminal according to claim 1, wherein the radiator comprises an antenna pattern printed on an outer surface of the base.
6. The built-in antenna module for a wireless communication terminal according to claim 1, wherein the upper base comprises a plurality of insertion projections on an upper surface thereof corresponding to insertion holes of the radiator.
7. The built-in antenna module for a wireless communication terminal according to claim 1, wherein the upper base comprises a plurality of vertical pillars on an undersurface thereof corresponding to a plurality of lower holes formed in the upper surface of the lower base.
8. The built-in antenna module for a wireless communication terminal according to claim 1, wherein the upper base comprises at least one insertion flap on an outer periphery thereof corresponding to insertion grooves formed on an outer periphery of the lower base.
9. The built-in antenna module for a wireless communication terminal according to claim 1, wherein the upper base and the lower base are bonded integrally with an adhesive to prevent sounds generated by the operator from leaking out of the base.
10. The built-in antenna module for a wireless communication terminal according to claim 1, wherein the upper base and the lower base are bonded integrally via ultrasonic welding to prevent sounds generated by the operator from leaking out of the base.
11. The built-in antenna module for a wireless communication terminal according to claim 1, wherein one of the upper and lower bases comprises a seating part depressed for precisely locating the operator.
12. The built-in antenna module for a wireless communication terminal according to claim 11, wherein the seating part comprises a predetermined dimension of sound emitting opening, and one of the upper and lower bases comprises a

sound passageway having an opening at an end facing a receiver to deliver the sound emitted from the sound emitting opening to the receiver of the terminal body.

13. The built-in antenna module according to claim 1, wherein the lower base comprises a plurality of projections corresponding to holes formed in the board.

14. The built-in antenna module according to claim 1, wherein the base is fastened with a fastening member such that the lower surface of the base is in surface contact with the upper surface of the board.

15. The built-in antenna module for a wireless communication terminal according to claim 1, wherein the base is made of insulation material.

16. The built-in antenna module for a wireless communication terminal according to claim 1, wherein the operator comprises at least one multi-actuator for selectively generating sounds or vibrations when power is supplied.

17. The built-in antenna module for a wireless communication terminal according to claim 16, wherein one of the upper and lower bases corresponding to the multi-actuator has an opening for delivering the generated sounds to a receiver of the terminal body.

18. The built-in antenna module for a wireless communication terminal according to claim 1, wherein the operator comprises at least one first actuator for generating sounds when power is supplied and at least one second actuator for generating vibrations when power is supplied.

19. The built-in antenna module for a wireless communication terminal according to claim 18, wherein one of the upper and lower bases corresponding to the first actuator has an opening for delivering the generated sounds to a receiver of the terminal body.

20. The built-in antenna module for a wireless communication terminal according to claim 18, wherein one of the upper and lower bases corresponding to the second actuator is sealed to deliver the generated vibrations through the base to the terminal body.

21. The built-in antenna module for a wireless communication terminal according to claim 18, wherein the lower base with the second actuator disposed therein comprises a plurality of vertical ribs in contact with an outer surface of the second actuator.
